CLAIM

The ornamental design for a huber safety needle assembly, as shown and described.

DESCRIPTION

FIG. 1 is a perspective view of a huber safety needle assembly, showing the assembly in a closed configuration and gripping portions in a first configuration;

FIG. 2 is a perspective view of the huber safety needle assembly, showing the assembly in an open configuration and gripping portions in a first configuration;

FIG. 3 is a front view of the huber safety needle assembly, showing the assembly in a closed configuration and gripping portions in a first configuration;

FIG. 4 is a front view of the huber safety needle assembly, showing the assembly in an open configuration and gripping portions in a first configuration;

FIG. 5 is a left-side view of the huber safety needle assembly, showing the assembly in a closed configuration and gripping portions in a first configuration, wherein a right-side view is a mirror image of the left-side view;

FIG. 6 is a left-side view of the huber safety needle assembly, showing the assembly in an open configuration and gripping portions in a first configuration, wherein a right-side view is a mirror image of the left-side view;

FIG. 7 is a rear view of the huber safety needle assembly, showing the assembly in a closed configuration and gripping portions in a first configuration;

FIG. 8 is a rear view of the huber safety needle assembly, showing the assembly in an open configuration and gripping portions in a first configuration;

FIG. 9 is a bottom view of the huber safety needle assembly, showing the assembly in a closed configuration and gripping portions in a first configuration;

FIG. 10 is a bottom view of the huber safety needle assembly, showing the assembly in an open configuration and gripping portions in a first configuration;

FIG. 11 is a top view of the huber safety needle assembly, showing the assembly in a closed configuration and gripping portions in a first configuration;

FIG. 12 is a top view of the huber safety needle assembly, showing the assembly in an open configuration and gripping portions in a first configuration;

FIG. 13 is a perspective view of a huber safety needle assembly, showing the assembly in a closed configuration and gripping portions in a second configuration;

FIG. 14 is another perspective view of a huber safety needle assembly, showing the assembly in a closed configuration and gripping portions in a second configuration; and,

FIG. 15 is a perspective view of the huber safety needle assembly, showing the assembly in an open configuration and gripping portions in a second configuration.

The broken line showing of parts of the drawings is included for the purpose of illustrating use and environment and forms no part of the claimed design.
